CLAIM

The ornamental design for a display device for furniture as shown and described.

DESCRIPTION

FIG. 1 is a front, right, top perspective view of a display device for furniture, showing our new design in a first state of use;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, right, top perspective view of the display device for furniture of FIG. 1, shown in a second state of use;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a front, right, top perspective view of the display device for furniture of FIG. 1, shown in a third state of use;

(Continued)

FIG. 16 is a front elevation view thereof;
 FIG. 17 is a rear elevation view thereof;
 FIG. 18 is a left side elevation view thereof;
 FIG. 19 is a right side elevation view thereof;
 FIG. 20 is a top plan view thereof; and,
 FIG. 21 is a bottom plan view thereof.
 The broken lines illustrate portions of the display device for furniture that form no part of the claimed design.
